UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

TRACK-FASTENING.

1,031,967.

Specification of Letters Patent. Patented July 9, 1912.

Application filed August 7, 1911. Serial No. 642,664.

To all whom it may concern:

Be it known that I, JOHN W. STEPHENSON, a resident of Toledo, in the county of Lucas and State of Ohio, have invented a new and useful Improvement in Track-Fastenings, of which the following is a full, clear, and exact description, reference being had to the accompanying drawings, forming part of this specification, in which—

10 Figure 1 is a view partly in side elevation and partly in vertical section showing my improved track fastening as applied to a rail brace; Fig. 2 is an end view thereof; Fig. 3 is a plan view; Figs. 4 and 5 are 15 views similar to Fig. 1, but illustrating two different modifications, Fig. 5 showing the application of the fastening to a rail joint; and Fig. 6 is an end view of the parts shown in Fig. 5.

20 My invention has relation to track fastenings, being more particularly an improvement upon the track fastening described and claimed in my Patent No. 1,010,971 dated Dec. 5, 1911. In that patent, I have 25 described and claimed a track fastening comprising a bendable key member adapted to be used in securing in place the member or members of a railway track structure. The present invention employs a bendable 30 key of somewhat similar character to that of the said patent, but contemplates its use in a different manner.

Referring first to that form of my invention shown in Figs. 1, 2 and 3, in which 35 the invention is shown as applied in securing a rail brace in position, the numeral 2 designates a portion of a railway track rail, 3 a rail brace, and 4 a base plate upon which the rail and brace are seated. The base 40 plate is shown as having lips or lugs 5, at one side of the rail for engagement with the base flange thereof and at the opposite side has an upward projection 6, which is formed with an undercut and longitudinally wedging inner face 7. The brace member 3 is 45 driven tightly between this face 7 and the adjacent side of the rail. 8 designates a bendable key member having a suitable driving head 9 at one end and which, in the 50 form shown in these figures, is driven through a curved opening 10, in an upward projection 11 on the base plate 4, and thence into a recess or opening 12, in the adjacent end of the brace 3. This opening 12 is also 55 shown as having a curved bending or de-

flecting wall. As the key member is driven through the opening 10 of the lug or projection 11, it is bent or kinked in the manner substantially as shown, and as its free end portion enters the recess 12, in the bracing member, such end portion is further bent or deflected. These two bends or deflections form a positive and secure lock against the working loose of the key. If, for any reason, it is desired to remove the brace, this 60 can be done by driving in the reverse direction on the head 9, with sufficient force to effect its withdrawal.

The modification shown in Fig. 4 is similar to that shown in the first three figures, except that the inner end of the key member 8^a, instead of being driven into a recess in the brace 3 is simply driven against the adjacent end of the brace 3^a.

In the modification shown in Figs. 5 and 6, the invention is shown as applied to a rail joint and the lug or projection 11 with its deflecting passage is omitted, the key member 8^b being driven through an opening 13 in the base member 14, having a curved 70 deflecting wall 15. The end portion of the key extends upwardly into a pocket or recess 16, in the rail-brace and joint-forming member 17, and coming into contact with the upper wall 18 thereof is bent or deflected 75 downwardly, as shown.

My invention provides a simple and practical form of track fastening which can be applied by an ordinary, unskilled laborer, all that is required being to drive the member firmly to its seat, the locking being 80 effected automatically. The key is tightly held by the bending or deflection of a portion or portions thereof which will not work 85 loose in use.

While I have shown my invention as applied to securing rail braces and rail joint-forming members, it will be readily understood that it may be adapted to securing other members of a track structure.

I claim:

1. In a railway track structure, the combination with a base member and a rail-engaging member, of a bendable key member driven through an opening in the base member and into a recess or opening in the rail-engaging member, the opening in the latter having means for bending a portion of the key in a manner to effect the locking of the same, substantially as described.

- 2
2. In a railway track structure, the combination with a base member and a rail-engaging member, of a bendable key member driven through an opening in the base member and into a recess or opening in the rail-engaging member, the openings having means for bending or deflecting portions of the key, substantially as described.
  3. In a track fastening, a member to be secured and another member, the latter having a key opening extending therethrough and a key driven through said opening into engagement with the member to be held and having its intermediate portion bent or deflected by the curved wall of the said opening, substantially as described.
  4. In a track structure, a base or tie plate having an upwardly projecting lug formed

with a key opening therethrough, said key opening having a curved key-deflecting wall, substantially as described.

5. In a track structure, a member to be secured and a seating member, the latter having a key opening therethrough, and a key driven through said opening into engagement with the member to be secured, the key having an intermediate portion bent or deflected within the said opening, substantially as described.

In testimony whereof, I have hereunto set my hand.

JOHN W. STEPHENSON.

Witnesses:

JOHN J. MANNING,
C. W. ERKERT.
